ARRANGEMENT IN ELECTRIC INDUCTION FURNACES WITHOUT A CLOSED FERRO-MAGNETIC CIRCUIT

Ludwig Dreyfus, Västerås, Sweden, assignor to
Allmänna Svenska Elektriska Aktiebolaget,
Västerås, Sweden, a corporation of SwedenApplication August 29, 1932, Serial No. 630,801,
and in Sweden August 29, 1931

2 Claims. (Cl. 219—47)

In electric high-frequency induction furnaces without iron cores it has previously been proposed to insert ferro-magnetic parts between certain conductors of the winding in order to affect the magnetic leakage and thereby reduce the eddy current losses in the winding. It has now been found that such parts, if inserted between the conductors of a winding provided with a ferro-magnetic shell highly contribute to an increase of the active magnetic flux, at the same time as its reducing action on the eddy current losses is considerably strengthened. The present invention therefore comprises the combination, in electrical induction furnaces without iron cores of a ferromagnetic shell surrounding the winding and ferromagnetic parts inserted between the separate conductors of the said winding.

One form of the invention is illustrated in the accompanying drawing, which shows one quarter of a furnace with a cylindrical winding in a vertical sectional view.

1 is the crucible, 2 the winding, 3 the magnetic shell and 4 the ferro-magnetic intermediary parts which preferably are laminated perpendicularly to the shell and have an increasing number of laminations towards the ends of said shell. The axis of the furnace is indicated by a vertical dash and dotted line and a horizontal plane through the centre of the winding, about which it is assumed to be symmetrically ar-

ranged, by a horizontal dash and dotted line. Lines of magnetic flux are indicated by dotted lines, which show how practically all that flux which does not pass through the portion of the shell projecting towards the furnace is conducted through the intermediary parts, which therefore considerably contribute to an increase of the active flux in the furnace, at the same time as they reduce the axial leakage and thereby the copper losses in a more efficient degree than hitherto known.

I claim as my invention:—

1. In electrical induction furnaces, a receptacle for the material treated, a winding surrounding said receptacle, a ferromagnetic shell surrounding said winding and leaving the interior of said receptacle substantially free, and ferromagnetic sheets substantially perpendicular to said shell inserted between different turns of the winding carrying the same current. 75

2. In electrical induction furnaces, a receptacle for the material treated, a winding surrounding said receptacle, a ferromagnetic shell surrounding said winding and leaving the interior of said receptacle substantially free, and 80 ferromagnetic parts laminated substantially perpendicularly to the shell inserted between different turns of the winding carrying the same current, the number of laminations increasing towards the ends of said shell. 85
